AMUSEMENT DEVICE

Andrew Bollak, Homer City, Pa.

Refiled for abandoned application Serial No.
605,764, April 16, 1932. This application August
14, 1933, Serial No. 685,029

4 Claims. (Cl. 46—40)

This invention relates to amusement devices and more particularly to such devices in which a dancing movement is accompanied by music.

This case has been filed in place of Serial No. 605,764, filed April 16, 1932, which became abandoned.

The invention consists in combining a motor-operated phonograph with a mechanism that operates one or more dancing figures synchronously, and in other structure related to a small portable amusement device.

The objects of the invention, among others, are: First, to provide a small portable amusement device producing music and showing dancing figures; second, to provide such a device in which the dancing figures are operated by the phonograph motor; third, to provide a protective housing, mounted on a base, that is easily and quickly broken down and reassembled; fourth, to provide a simple mechanical adjustment by which the phonograph may be played alone or with the dancing figures; fifth, to provide a small housing with windows to cover the dancing figures and through which the dancing figures are visible; and sixth, to provide a low cost, simple, durable, and robust construction throughout.

Reference is now made to the drawings in which Fig. 1 is a front elevation,

Fig. 2 is a similar view with the front cover turned down,

Fig. 3 is a horizontal section on the line 3 of Fig. 2,

Fig. 4 is a view similar to that of Fig. 2 but with the walls of the housing all turned down and the housing for the dancing figures also turned down,

Fig. 5 is a horizontal section through the two pulleys shown at the left in Fig. 3, and

Fig. 6 is a vertical section through the operating shaft shown at the right in Fig. 5.

Like numerals of reference refer to like parts throughout the drawings in which a housing 5 is supported on four legs 6, which support the base 7 on which are hinged by the hinges 11 to turn outwardly and downwardly the four vertical

walls of the housing comprising the front cover 8, the rear wall 9, and the end walls 10. A top cover 12 is provided with a bead 13 inset from the edge which is adapted to fit over and hold together the top edges of the vertical walls of the housing

and which also supports hooks 51 adapted to interlock with eyes fastened on the vertical walls. In the position of the parts as shown in Fig. 1 the device is adapted for storage or portability with all the parts protected and closed against dust or dirt. The front cover 8 has been turned

down in Fig. 2 to expose the amusement device. A phonograph of a conventional type adapted for flat disc records and wound with a crank is shown at the extreme right. To the left of the phonograph and connected with the phonograph by an aperture is a housing 14 which contains the operating mechanism of the amusement device. The phonograph is designated by the numeral 15. Within the housing 14 is a base 17 access to which is had by a door 19 mounted on the hinges 20. 60 This door is provided with a slot adapted to receive the eye 23 mounted on the end wall of the housing 14 and a pivoted hook 24 mounted on the inner wall and adapted to interlock with the eye. Mounted on the housing 14 is a housing 26 having a roof 27 and two similar glass windows 28, this housing being mounted on the hinges 39 and adapted to be turned to the left to expose the dancing figures 38. Each group of figures 38 represents human dancers in European folk dancing costumes. Each group is mounted on a flexible base 32 which is rotatably mounted, the one at the left being mounted on the shaft 29 and the one at the right being mounted on the shaft 30. 65 The vertical shafts rotate in apertures in the roof 70 25 of the housing 14 and are pivotally mounted in flanged bearings 31 mounted on the base 17. A pulley 33 fast on the shaft 29 is adapted to receive the belt 37 which also travels over the pulley 34 which is fast on the shaft 30 by means of 75 the locking pin 35. An idler pulley 36 is also mounted on the vertical shaft 30. The housing 14 and the phonograph 15 are connected by a housing 40, 41 in which a belt 42 travels, being selectively connected at the left with the fixed 80 pulley 34 in which position it operates both sets of dancing figures 38, or with the pulley 36 in which case the figures do not operate. The belt 42 passes through an aperture 44 in the phonograph wall and turns with a vertical pulley 43 85 mounted on the vertical operating shaft of the phonograph which obviously is actuated by the 90 spring of the phonograph motor.

The operation of the device is now clear. To operate the dancing figures simultaneously with the playing of the phonograph the left end of the belt 42 is simply sprung off the idler pulley 36 and on the pulley 34 which turns with the pulley 33 so that when the phonograph is started or stopped the dancing figures start or stop synchronously. I have provided therefore a simple amusement device which produces music and dancing figures simultaneously at low cost and with the same portability as is possessed by a phonograph so 100 105 110

that it can be easily carried about and set up in the street or in a hall.

Changes in details of construction will readily occur to those skilled in the art, so I do not limit myself except as in the appended claims.

5 I claim:

1. An amusement device comprising in combination, a phonograph, a rotating platform, said platform consisting of a flexible disc, a dancing figure eccentrically mounted on said platform, 10 and means for rotating said platform connected with the actuating mechanism of a phonograph.

2. An amusement device comprising in combination, a phonograph, a rotating platform, said platform consisting of a flexible disc, a dancing 15 figure eccentrically mounted on said platform, said platform being mounted on a vertical shaft, a pulley on said vertical shaft, and a belt mounted on said pulley and connected with the actuating mechanism of the phonograph.

20 3. An amusement device comprising in combination, a phonograph, a plurality of rotating

platforms, dancing figures eccentrically mounted thereon, a vertical shaft having a pulley thereon connected with each platform, a belt connected with pulleys of said shafts, a pulley mounted on the vertical operating shaft of the phonograph, and a belt connected with one of said pulleys and with the pulley mounted on the vertical operating shaft of the phonograph.

4. An amusement device comprising in combination, a phonograph, a plurality of rotating 80

platforms, dancing figures eccentrically mounted thereon, a vertical shaft having a pulley thereon connected with each platform, a belt connected with pulleys of said shafts, a pulley mounted 85

on the vertical operating shaft of the phonograph, a belt connected with one of said pulleys 90

and with the pulley mounted on the vertical operating shaft of the phonograph, and an idler pulley mounted concentrically with one of said platform-connected pulleys.
